DESIGN FOR A BATHTUB

Richard G. Fensch, Mansfield, Ohio, assignor to
The Humphries Manufacturing Company,
Mansfield, Ohio, a corporation of Ohio

Application June 24, 1941, Serial No. 101,640

Term of patent 14 years

To all whom it may concern:

Be it known that I, Richard G. Fensch, a citizen of the United States, residing at Mansfield, in the county of Richland and State of Ohio, have invented a new, original, and ornamental Design for a Bathtub, of which the following is a specification, reference being had to the accompanying drawing, forming a part thereof.

The single figure of the drawing is a perspective view of a bathtub embodying my design.

I claim:

The ornamental design for a bathtub, as shown.

RICHARD G. FENSCH.
